DESIGN FOR A BOTTLE

Charles Davis Little, Chattanooga, Tenn., assignor to Seminole Flavor Company, Chattanooga, Tenn., a corporation of Tennessee

Application February 23, 1934, Serial No. 50,830

Term of patent 14 years

To all whom it may concern:

Be it known that I, CHARLES DAVIS LITTLE, a citizen of the United States, residing at Chattanooga, in the county of Hamilton and State of Tennessee, have invented a new, original, and ornamental Design for a Bottle, of which the following is a specification, reference being had to the accompanying drawing, forming a part thereof.

In the drawing,

The figure is a side view in elevation of a bottle, showing my new design.

I claim:—

The ornamental design of a bottle, substantially as shown.

CHARLES DAVIS LITTLE.
